UNITED STATES PATENT OFFICE.

FRANCIS C. OSBORN, OF DETROIT, MICHIGAN, ASSIGNOR, BY MESNE ASSIGNMENTS, TO NATIONAL CASH REGISTER COMPANY, OF JERSEY CITY, NEW JERSEY, A CORPORATION OF NEW JERSEY.

TIME-CLOCK FOR CASH-REGISTERS.

SPECIFICATION forming part of Letters Patent No. 790,654, dated May 23, 1905.

Application filed August 20, 1900. Serial No. 27,417.

To all whom it may concern:

Be it known that I, FRANCIS C. OSBORN, a citizen of the United States, residing at Detroit, county of Wayne, State of Michigan, have invented a certain new and useful Improvement in Time-Clocks for Cash-Registers; and I declare the following to be a full, clear, and exact description of the invention, such as will enable others skilled in the art to

10 which it pertains to make and use the same, reference being had to the accompanying drawings, which form a part of this specification.

My invention relates to improvements in time-clocks for cash-registers, and is shown 15 in the accompanying drawings, in which—

Figure 1 is a view of a cash-register with a clock in place in the register. Fig. 2 is a horizontal cross-section showing the manner of supporting the clock in the case. Fig. 3 is a rear 20 view of the supporting-plate, showing the winding-key exposed and the setting-key in dotted lines to represent the same as covered. Fig. 4 is a section on line $\alpha\alpha$. Fig. 5 is a sectional view of the setting-plunger from line γ of Fig. 4. Fig. 6 is a view showing the cam 25 for lifting the plunger. Fig. 7 is a detail showing the construction of the hour-hand, and Fig. 8 is a detail showing the construction of the third hand.

30 In the drawings, A represents the case of the register, and A' an upstanding ornamental plate on the top of the register. In machines with which the time-clock is used this plate is provided with a recess α of a size to receive 35 and fit the clock. The depth of the recess is usually less than the depth of the clock, so as to allow the clock to stand out a sufficient distance to provide for operating the plunger D in front of the plate A'. This form of construction is not necessary, however, as a recess may be provided for the plunger in the 40 face of the plate above the clock.

B represents the case of the clock, and b a lock the bolt of which enters the clock-case 45 and holds it in the recess α .

b' represents the winding-key of the clock, and in Fig. 3 this key is shown as exposed

through an opening a' in the rear wall of the recess α . This form of construction is to provide for winding the clock without removing 50 it from the recess, which can only be done by the person holding the key, usually the proprietor.

b^2 represents in dotted lines the setting-key, which can only be operated by unlocking and 55 removing the clock.

The opening through which to operate the winding-key may be dispensed with where the proprietor does not object to unlocking the 60 clock for the purpose of winding.

C represents an interior plate, in front of and upon which the additions to the usual 65 clock mechanism employed by me are supported.

C' is a frame which forms a bearing at c for the journals to which the hands are attached. The frame also constitutes a support and 70 guide for the plunger D.

c' is the sleeve to which the hour-hand c^2 is attached, and c^3 the journal to which the minute-hand c^4 is fixed.

c^6 is a double-faced cam sleeved upon the bearing c .

c^4 is a third hand attached to the sleeve c^5 . The sleeve c^5 is integral with the cam c^6 and 75 is allowed an endwise movement with the cam, by which endwise movement it carries the third hand c^4 to or from the hour-hand, which stands next to it. The sleeve c^5 is mounted with such closeness of fit to the extension-sleeve of the fixed frame C' as to hold the hand stationary when disconnected from the 80 moving parts of the clock.

To carry out the plan of my invention, it is necessary for the third hand c^4 to travel at 85 times with and directly under the hour-hand and be carried forward with it and at other times to be left stationary to mark the time.

To provide for engaging the hands together for the purpose mentioned, I provide the hour-hand with a horizontal lug c^7 and the third hand with a vertical lug c^8 , the lugs being so located that when the sleeve c^5 and the third hand are moved outward to their limit the lug 90

c^8 will come in the path of the lug c^7 and the hour-hand be thereby caused to carry the third hand forward with it against the friction between the sleeve c^6 and the fixed extension so long as the third hand remains at the outward end of its adjustment. The normal position of the parts is that in which the hour and third hands are engaged and traveling together. The means for disengaging these hands, and thereby leaving the third hand stationary, consists of the plunger D, arranged to be pushed down from above the clock. The upper end of the plunger travels in a way in the frame C', and the lower end moves up and down in a way in the stud C², that extends forward from the plate C. Between the frame C' and the stud C² the plunger is split and expanded into a ring C³.

c^{10} c^{10} are cams extending inward from the ring and are beveled in opposite directions, so that one will operate upon one face of the cam c^6 and the other upon the other face. This construction is such that when the plunger is moved down the cam c^6 is moved inward, carrying the third hand out of engagement with the hour-hand, allowing the third hand to stop and indicate the time when the plunger was set down. As these clocks are usually used to indicate to the proprietor the time when the store is opened, to indicate such time the clerk on entering the store in the morning pushes the plunger down, thereby stopping the third hand in position to indicate the exact time. The hand remains in this position until the proprietor has had an opportunity to view it, after which he may raise the plunger to move the third hand into position to be picked up by the hour-hand when it again passes it, which will be at the time in the evening corresponding to the time in the morning when the hand was stopped. To provide, however, for automatically resetting the clock without the necessity for withdrawing the plunger by hand, I employ means for lifting the plunger sometime within the twelve hours after the clerk has set it after the proprietor has had an opportunity to note the time when the store was opened in the morning. For this purpose I provide the plunger with the parallel arm D'. The lower end of this arm is arranged to come in contact with the cam E. This cam is attached to a gear e, which is in mesh with gear e', mounted on the sleeve carrying the hour-hand. The gear e' is half the size of the gear e, so that the cam E revolves once with every two revolutions of the hour-hand, or once in twenty-four hours. The cam is cut away for about half its circumference, with a direct offset at e^2 and with a lifting-incline at e^3 . Thus for twelve hours the plunger, if up, can be pushed down, and at the end of the twelve hours it will be automatically lifted and cannot be again pushed down for twelve hours. The cam is set so that it will lift the plunger and throw the third

hand in position to engage the hour-hand any time prior to the time when they come together. Thus if the usual hour for opening the store is seven in the morning the cam will be arranged to clear the plunger at, say, 70 five a. m., and the plunger will be pushed down by the clerk on opening the store and will remain down until five in the evening, when it will be automatically raised and the third hand be put in position to be picked up 75 by the hour-hand again at seven in the evening.

My invention is an improvement of the construction heretofore used by which the time of opening is indicated by the stopping of the clock. In the use of such construction the use of the clock for general purposes is lost and the clock must be set each day. With my construction the clock runs continually and only the third hand is stopped, while means are provided for picking it up again 85 during the day to be in position to be again stopped on the following morning.

It will be seen from the foregoing description of the plunger D and the cam E that the third hand is prevented from being stopped 90 during a portion of the twenty-four hours. The object of this construction is to prevent a clerk from stopping the third hand at a time previous to the time he should operate the plunger to stop it. Were this provision 95 not made, the clerk could stop the third hand at seven o'clock in the evening, for example, and if he failed to come in at the required time, at seven o'clock in the morning, the indication of the clock would not show such 100 tardiness.

If it is desired to indicate the time at which a second clerk should arrive—say at noon or in the evening—the proprietor after noting the position of the third hand can set the 105 clock forward twelve hours in the ordinary manner by the resetting-key, when it will be ready for a clerk arriving at noon or in the evening.

It will be noted that a spring d is arranged 110 to hold the plunger D by friction in any desired position. This spring is more particularly designed to hold the plunger from moving downward by its own weight, and to make it more effective for this purpose a nick or depression may be made in the plunger to receive the spring when the plunger is in its uppermost position, as shown in Fig. 4.

The cam E may also be placed directly upon the sleeve c^6 , thus making a revolution once 120 in twelve hours instead of once in twenty-four hours without departing from my invention and without materially weakening the effectiveness of the device. I therefore claim such construction as within the scope of my invention. 125

What I claim is—

1. In a time-registering clock, the combination with the hour-hand, of a third hand journaled concentrically with the hour-hand and 130

adapted to be moved over the same path therewith, means for positively connecting the third hand with the hour-hand as they come together, and means for positively moving the third hand out of the path of propulsion of the hour-hand whereby to indicate the exact position of the hour-hand at the time of disconnection.

2. In a time-registering clock, the combination with the hour-hand, of a third hand journaled concentrically with the hour-hand, lugs for locking said hands positively together to cause the third hand to rotate with the hour-hand, and means for positively moving the third hand in such manner that its lug is moved out of the path of propulsion of the lug on the hour-hand whereby the hour-hand will move on independently of and without any subsequent effect upon the third hand.

3. In a time-registering clock, the combination of the hour-hand provided with a locking-lug; the sleeve to which the said hand is attached; the third hand provided with a locking-lug, arranged to lock with the lug on the hour-hand as the hands come together in making the circuit; the frame provided with a sleeve to form an outside bearing for the said hour-hand sleeve; the double-faced cam for moving the third hand; the sleeve mounted on said double-faced cam; and means for moving said cam laterally, substantially as and for the purpose described.

4. In a time-registering clock, the combination of the frame provided with a hollow bearing; the hour-hand having a bearing on the inside of said hollow bearing; the third hand having a bearing on the outside of said hollow bearing, said third-hand bearing having a lateral movement to bring the said hands in the connection whereby the third hand is caused to travel with the hour-hand; the cam for restoring the connection between said hands; the gears for driving said cam; and means operated by said cam for moving said hands into connection, substantially as and for the purpose described.

5. In a time-registering clock, the hour-hand, the third hand, means for adjusting the hands to and from each other, means arranged to engage the hands as they pass when they are at the near end of the said adjustment and to allow them to pass without engagement when at the far end of their adjustment, and means for automatically returning the hands to the near position at a predetermined time, substantially as described.

6. In a time-registering clock, the combination with the hour-hand, of a third hand, means for moving the hour-hand and the third hand positively together, means for positively moving the third hand out of the path of propulsion of the hour-hand, and means connected with the hour-hand for automatically moving the third hand back into the path of propul-

pulsion of said hour-hand at a predetermined time, substantially as described.

7. In a time-registering clock, the hour and third hands, means for moving the said hands together, means for stopping the third hand, at any time during certain predetermined hours and means for preventing the stopping of the third hand, except during the predetermined hours, substantially as described.

8. In a time-registering clock, the clock mechanism, the hour and third hands, means for engaging and moving the said hands together, the plunger, the cam arranged to disengage the hands, and means connected to the clock mechanism and arranged to prevent the operation of the plunger except during predetermined hours, substantially as described.

9. In a time-registering clock, the hour-hand, the third hand, said hands having relative coupling or uncoupling movements to and from each other, the double-faced cam for moving the hands to and from each other, the plunger arranged to act upon both faces of the cam, and means for engaging the said hands together when at their near position, substantially as described.

10. In a time-registering clock, the hour-hand, the third hand, the double-faced cam, means operated by the movement of the cam for connecting the hands and the plunger provided with the ring surrounding the cam, substantially as described.

11. In a time-registering clock, the plunger, the third hand, means operated by the plunger for stopping the third hand, and the cam for lifting the plunger arranged to make one revolution in twenty-four hours, substantially as described.

12. In a time-registering clock, the third hand, means for stopping the hand, and means for automatically resetting the stopping device once in twenty-four hours, substantially as described.

13. In a time-registering clock, the third hand, means for stopping the third hand, and a cam arranged to reset said stopping device once in twenty-four hours, substantially as described.

14. In a time-registering clock, the hands, means for stopping a hand or hands to indicate the time of such operation, and means operated by the clock mechanism for resetting the stopping device within twenty-four hours, substantially as described.

15. In a time-registering clock, the hour-hand, the third hand, means for engaging and moving the hour and third hands together, means for disengaging the hands to stop the third hand, and means for automatically resetting the third hand in position to engage the hour-hand before they again come together, substantially as described.

16. The combination of a stop-indicating clock, provided with rewinding means and re-

setting means, with a holding-plate provided with a recess for said clock so arranged as to permit the rewinding of the clock but to prevent the resetting thereof unless removed from said recess, and means for locking said clock in said recess, substantially as set forth.

17. In a stop-indicating mechanism for clocks, a clock mechanism, an hour-hand, a minute-hand, and a third hand moving with one of the other hands arranged to be stopped at will during a portion of a given period, as the twenty-four hours of a day, and mechanism automatically operated by the clock mechanism and arranged to prevent the stopping of said hand during a definite portion of said period, substantially as set forth.

18. In a time-registering clock, a clock mechanism, the third hand, means for stopping the third hand at will, and means operated by the clock mechanism arranged to automatically reset said stopping device during a given period of time, substantially as set forth.

19. In a time-registering clock, a clock mechanism, the third hand, means for stopping the third hand, and the cam connected to the clock mechanism arranged to reset said

stopping device during a given period of time and to hold said stopping device from operative action during a predetermined portion 30 of said period of time, substantially as set forth.

20. In a stop-indicating mechanism for clocks, the combination with a clock mechanism, of a hand connected to and moving therewith, an independent hand arranged to move with the first-mentioned hand and to be disconnected therefrom, and means connected to the clock mechanism for preventing such disconnection except at predetermined periods. 35 40

21. In a stop-indicating mechanism for clocks, a clock mechanism, a hand connected thereto, another hand arranged to be coupled to and uncoupled from the first-mentioned hand, manually-operated means for uncoupling the hands, and means connected to the clock mechanism for automatically recoupling the hands.

In testimony whereof I sign this specification in the presence of two witnesses.

FRANCIS C. OSBORN.
